CLAIM

The ornamental design for an automobile, as shown and described.

DESCRIPTION

FIG. 1 is a front and left side perspective view of an automobile;

FIG. 2 is a left side elevational view thereof;

FIG. 3 is a rear and right side perspective view thereof; and

FIG. 4 is a front perspective view thereof.

The broken-line representation in the drawings is for illustrative purposes only and forms no part of the design.

FIG. 2

FIG.4
